LAPPING BLOCK

Foster F. Hillix, Lakewood, Ohio, assignor to The
American Steel and Wire Company of New
Jersey, a corporation of New Jersey

Application April 19, 1935, Serial No. 17,319

6 Claims. (Cl. 51—205)

This invention relates to lapping blocks, and more particularly to those which are used for grinding and/or polishing relatively hard surfaces, such as metal or glass, whether plane or curved.

Heretofore it has been the practice, in obtaining smooth surfaces, to reduce the same by cutting or lapping operations employing wheels, usually of the abrasive variety, and lapping heads, wherein the cutting is done by a multiplicity of cutting points of irregular shape. The surfaces thus obtained are characterized by having an unevenness identified by such terms as "grain marks", "orange peel", etc., which depends, in part, upon the fineness, or coarseness, of the wheel and/or abrasive employed. Coarse wheels and abrasives are employed initially because they remove the stock rapidly, and finer wheels and/or abrasives substituted therefor until the desired high finish is obtained.

One of the worst disadvantages of lapping blocks heretofore used is that hard particles that are broken off, or cut from, the surface of the object being ground and/or polished become entrapped between the same and the lapping block, producing a scoring or marring effect. If, for example, a roll is being polished, and such scoring takes place, the resulting effect is in the form of a comparatively deep serpentine groove, which may only be removed at the cost of considerable time, labor and material.

It is one of the objects of the present invention to provide a novel lapping block for grinding and/or polishing surfaces, such as metal, glass, etc., which presents to the work-piece a rigid cutting member, and one which does not merely grind off the irregular surfaces; but, on the other hand, produces a flat smooth surface of high finish, which is free from the usual defects, such as "orange peel", etc.

Another object is the provision of a device of the class described which may be easily and cheaply manufactured, and one which will prove very durable in service.

These and further objects will be apparent after referring to the drawing, in which:

Figure 1 is a plan of the device of the invention.

Figure 2 is an elevation.

Figure 3 is a sectional view on the line III—III of Figure 1.

Figure 4 is a sectional elevation showing a means of assembling one of the elements.

Figure 5 is an enlarged detail.

Figure 6 is a perspective of the device in operation.

Referring more particularly to the drawing, the numeral 1 designates a block which is composed of any suitable material, preferably non-metallic and non-hygroscopic; for instance, a durable fiber, or bakelite. This block 1 may be of any suitable shape (being shown in the present instance as rectangular), and is provided with a plurality of recesses 2 in each of which there is disposed one of the novel cutting elements of the invention. These cutting elements, which are indicated in the drawing at 3, are in the form of packed metallic wool, of which that grade known as Commercial No. 000 steel wool is found very suitable.

For certain grades of finish I have found it advantageous to mix other and softer fibers with the metallic wool fibers. As an example, the softer fibers may be sheep's wool, cotton, linen, or hemp, in varying proportions; that is, for the rougher cuts it is only necessary to mix a few of the softer fibers with the metallic wool fibers; while for the finishing cuts a larger number are included.

Whether the metallic wool fibers are used alone, or in combination with the softer fibers, they preferably protrude slightly from the recesses 2, as shown at 3a.

In order to pack the cutting elements 3 tightly into the various recesses 2, they are first rolled into rods of cylindrical shape, as shown in Figure 30 1, and in such a manner that as many of the fibers as possible are extended in one direction; that is to say, longitudinally of the roll. Each of these small rolls of fibers 3 is placed in a cylinder or tube 4, as shown in Figure 4.

The cylinder or tube 4 is then placed over one of the recesses 2 in the block 1 and forced therewith by means of a plunger 5, which is struck with a mallet or other soft hammer. The cutting elements 3 are then sheared off at their outer ends in such manner as to protrude therefrom, as stated previously. After all of the recesses 2 have been filled, the block 1 is preferably immersed in a liquid binder which is adhesive and insoluble in the particular material used as a lubricant in the grinding and/or polishing operations. Some suitable binders are bakelite, resinoid, shellac, silicate of soda, waterproof glue (such as casein glue or animal glue), vulcanized rubber, some of the harder varieties of wax and low-melting-point solder. The block 1 is kept immersed in the liquid binder until it has completely filled all of the interstices of the fibers in the recesses 2, after which it is removed and allowed to dry and harden.

If necessary, the previously immersed block 1 can then be baked to secure additional hardness. For example, bakelite resinoid has been found by experiment to be a very satisfactory binder, and when baked to a temperature of 300 degrees F. is sufficiently polymerized to have the desired characteristics. This binder having formed into a solid mass, completely fills the interstices between the fibers of the cutting elements 3 and serves a dual purpose; first, in that it maintains the fibers in a vertical position, thereby preventing them from bending over in the manner of the bristles of a brush; and secondly, in that it is porous and portions thereof between the fibers break off or wear away, leaving cavities or cut-out portions 6 in the faces 7 of the cutting elements 3. These cavities 6 serve to retain the cutting from the surface of the object being ground and/or polished, and result in the prevention of marring, or scoring.

The metallic wool fibers, whether used alone or in combination with the softer fibers, are thus held in a vertical position to produce a buffed or finished surface by actual cutting, rather than by buffing. If this were not possible, the fibers would bend over and only round off the irregularities in the surface of the object, and thereby produce an unevenness of the type previously referred to as "orange peel", which, while sometimes apparent to the eye, is more frequently too minute to be perceived.

In practice, one or more blocks 1, with the cutting elements 3 protruding therefrom, as at 3^a, is suitably mounted to effect an oscillatory movement over the objects being ground and/or polished. Referring to Figure 6 of the drawing, a machine is disclosed which satisfactorily serves to impart this desired movement. This machine comprises a holder 10 having a plurality of recesses 12 in each of which one of the blocks 1 is adapted to seat. A satisfactory method of retaining the blocks 1 in the recesses 12 is by the use of glue, although mechanical expedients may be utilized. The holder 10 is journaled in any suitable manner to one end of a shaft 13, which is connected on its other end to a shaft 14, by means of a coupling 15. The shaft 14 is reciprocably supported in any suitable manner by a suitable frame (not shown). An unbalanced pulley

16 is connected to the shaft 13 and driven through a power belt 17 from a suitable prime mover. Upon rotation of the unbalanced pulley 16 the blocks 1 are oscillated in a manner very suitable for grinding and/or polishing. A suitable loose abrasive is employed between the blocks 1 and the workpiece in order to facilitate the grinding and/or polishing. This abrasive is preferably used with oil or emulsion.

While I have shown and described several specific embodiments of my invention, it will be understood that I do not wish to be limited exactly thereto, since various modifications may be made without departing from the scope of my invention, as defined in the following claims.

I claim:

1. A lapping block comprising a body having at least one recess, and fibrous material disposed in and protruding from said recess, said fibrous material being composed of at least some metal fibers.

2. A lapping block comprising a body having at least one recess, and fibrous material disposed in and protruding from said recess, said fibrous material being composed of at least some metal fibers and impregnated with a binding agent.

3. A lapping block comprising a body having at least one recess, and fibrous material disposed in and protruding from said recess, said fibrous material being composed of a mixture of metallic and vegetable fibers.

4. A lapping block comprising a body having at least one recess, and fibrous material disposed in and protruding from said recess, said fibrous material being composed of a mixture of metallic and animal fibers.

5. A lapping block comprising a body having at least one recess, and fibrous material disposed in and protruding from said recess, said fibrous material being composed of a mixture of metallic and vegetable fibers impregnated with a binding agent.

6. A lapping block comprising a body having at least one recess, and fibrous material disposed in and protruding from said recess, said fibrous material being composed of a mixture of metallic and animal fibers impregnated with a binding agent.

FOSTER F. HILLIX.
